UNITED STATES PATENT OFFICE.

ALFRED L. EUSTICE, OF CHICAGO, ILLINOIS.

INCLOSED SAFETY-FUSE.

1,278,893.

Specification of Letters Patent. Patented Sept. 17, 1918.

Application filed August 2, 1915. Serial No. 43,077.

To all whom it may concern:

Be it known that I, ALFRED L. EUSTICE, a citizen of the United States, residing at Chicago, in the county of Cook, and State of Illinois, have invented certain new and useful Improvements in Inclosed Safety-Fuses, of which the following is a specification.

My invention relates to inclosed safety fuses used for the protection of electric circuits, and refers particularly (although not exclusively) to cartridge fuses of the non-renewable type.

Inclosed safety fuses are of two generally well-known types,—first, those in which the fusible link may be renewed by the user of the fuse after the latter has blown, although the same fuse casing and other parts may be used repeatedly, and, second, those of the non-renewable type in which the entire fuse is supposed to be discarded after it has blown a single time. There are advantages in each of these two general types of fuses. The renewable type utilizes the same parts, with the exception of the fusible link, many times, and thus the cost to the user for each blow-out is greatly reduced. At the same time, in a properly constructed fuse of this type the fire hazard is greatly reduced over what it is when a fuse not intended to be renewed by the user is improperly renewed by various crude means which may be at the disposal of the user.

Under certain circumstances users of inclosed fuses desire to eliminate all possibility of improper renewal of the fuse by using a type of fuse which cannot be tampered with but must be discarded after it has been blown a single time.

It is one of the objects of my invention to provide an inclosed fuse in which a new link cannot be inserted in the fuse without destroying the parts thereof, so that the fuse would be inoperative, while at the same time I have embodied in my improved fuse various features of construction which cause it to operate most satisfactorily under various conditions. Among these features may be mentioned the use of a link having preferably three portions of restricted cross-sectional area therein, at least one of these portions being located in an air chamber within the fuse casing and other restricted portions being located in chambers which are provided with a non-conducting filling. It has been found that in rating tests a fuse

will operate much more accurately when the fuse link is surrounded by air than when it is surrounded by a non-conducting filling material, while under short-circuit tests the volatilized gases are more quickly condensed when a filling material is employed than is the case when such is absent. In cartridge fuses in which no filling material is employed it is customary to release the gases slowly through restricted vent passages, thereby reducing the noise of the fuse under short circuit, and aiding to prevent the explosion of the fuse. When a fuse is made without a venting system, however, it becomes increasingly important to quickly condense the gases formed on blowing the fuse. In the non-renewable fuse of my present invention I have therefore employed filling material in contact with part of the link, thus avoiding the use of the expensive venting system which is used in renewable fuses in which no filling should be employed.

A further object of my invention consists in the employment within the fuse casing of means for preventing the renewal through the casing of the electrical connection between the terminals after the fuse has once been blown.

These and other objects of my invention will be more readily understood by reference to the accompanying drawings, in which—

Figure 1 is a side elevation of a fuse showing a preferred embodiment of my invention:

Fig. 2 is a longitudinal section through the fuse shown in Fig. 1;

Fig. 3 is a longitudinal section through the fuse shown in Fig. 1 but taken at an angle of 90° from the section shown in Fig. 2;

Fig. 4 is a transverse section taken on the line 4—4 of Fig. 2; and

Fig. 5 is a transverse section taken on the line 5—5 of Fig. 3.

The fuse casing 10, of fiber or other suitable insulating material, is engaged at its ends by the washers 11, each of which is provided with a slot or aperture 12 for the passage therethrough of the fusible link 13, which is preferably flat and constructed of zinc or other suitable metal. The portions 14, 14 of the link 13 engage the outer faces of the washers 11, 11, and are continued into the portions 15, 15, which engage the outer surface of the end portions of the casing 10. A cap 16 fits over each end of the casing 10,

and the edge 17 of the skirt portion of each cap 14 is bent into a groove 18 formed in the outer surface of the casing 10. It will be observed that each cap 16 forces the portion 14 tightly against the outer surface of the washer 11, and also that a tight engagement is formed between the portion 15 of the link 13 and the inner surface of the skirt of the cap 16. In order to prevent the cap 16 from 10 rotating, and also in order to more securely anchor each end of the fusible link in position, a triangular indentation 19 is punched from the cap into the body of the casing 10 and carries with it a portion of the fusible 15 link, as is clearly apparent in Fig. 2. In order to assist in the electrical connection between the skirt of the cap 16 and the end portion 15 of the fusible link 13, the aperture which is caused by forming the indentation 19 is 20 filled with solder 20.

The interior of the fuse casing 10 is divided by means of the partition washers 21 into three chambers, namely, a central chamber 22 and two end chambers 23. The partition washers 21 are preferably constructed of hardened steel or the like in order to be impenetrable by a drilling tool. These washers are provided with suitable slots or apertures 24 through which the fusible link 30 13 passes. The chambers 23 are filled with a granulated non-conducting filling material 25, of asbestos, plaster of Paris, lime, or the like, and the chamber 22 is left without filling material of any kind but is preferably 35 provided with a spacer tube 26, of fiber or other similar material, which engages at its ends the partition washers 21 in order to hold the latter in position, the filling material 25 within the chambers 23 serving to 40 hold the partition washers 21 against the ends of the spacer tube 26. It will be understood that any other method of holding these partition washers in position could be employed without departing from the spirit 45 of my invention.

The fusible link 13 is provided with apertures 27 and 28 therein, thereby forming in the fusible link portions of constricted cross-sectional area, so that on passage of an 50 electric current through the link the latter will tend to melt at these constricted portions, and when the current is of sufficient amount to constitute a short circuit, the link will melt at all three constricted portions, 55 thereby separating from the balance of the link the intermediate portions between the constricted portions without volatilizing or melting said intermediate portions.

As previously pointed out, it is possible to 60 rate a fuse link for over-load conditions much more accurately when the link is surrounded by air as the heat conductivity of the latter is practically constant, whereas if the fusible link is surrounded by a non-conducting filling material the contact of the

latter with the link is very variable, and thereby varies the operation of the fuse under over-load conditions.

In my improved fuse when the latter is subjected to over-load it melts at the constricted portion formed by the central aperture 27 for the reason that the constricted portions formed by the apertures 28 and the portions of the fuse immediately adjacent thereto are engaged by the filling material 25, which serves to conduct the heat away from the link, and thereby prevents the melting of the latter at these portions under the same circuit conditions which will cause the fuse to melt at the constricted portion formed by the aperture 27. 70 75 80

Under short-circuit conditions, on the other hand, where the fuse is subjected instantaneously to the action of a large amount of current the link will simultaneously melt at all three of its constricted portions, the intermediate portions of the link between these constricted portions being separated from the rest of the link without volatilization, thereby greatly reducing the amount of 90 volatilized metal. The gases formed, however, are quickly cooled by the action of the filling material 25, so that it is unnecessary to provide a venting system for the fuse. 85

It will be apparent to those skilled in the art that many changes could be made in the detailed construction of the inclosed fuse which I have described without departing from the spirit or scope of my invention as defined in the appended claims. 95 100

What I claim is:

1. In an inclosed fuse, the combination of a casing, terminals at the ends of said casing, a partition transversely disposed within said casing whereby the latter is divided into a pair of chambers, a fusible link extending through said chambers and between said terminals, said link having in each of said chambers a portion more readily fusible than the rest of said link upon 105 passage of an electric current therethrough, and a non-conducting filling material in one but not both of said chambers. 110

2. In an inclosed fuse, the combination of a casing, terminals at the ends of said casing, a hardened steel partition transversely disposed within said casing and dividing the latter into a pair of chambers, a fusible link extending through said chambers and between said terminals, said link 115 having a portion of constricted cross-sectional area within each of said chambers, and a non-conducting filling in one but not both of said chambers. 120

3. In an inclosed fuse, the combination of 125 a casing, terminals at the ends of said casing, a pair of transversely disposed partitions within said casing, whereby the latter is divided into a central and two end chambers, a fusible link extending through said 130

chambers and between said terminals, said link being constricted in at least two of said chambers, and a non-conducting filler in at least one but not all of said chambers, a 5 constriction of said link being in a chamber containing the filler.

4. In an inclosed fuse, the combination of a casing, terminals at the ends of said casing, a pair of transversely disposed 10 hardened steel partitions within said casing, whereby the latter is divided into a central and two end chambers, a fusible link extending through said chambers and between said terminals, said link being constricted in at least two of said chambers, and a non-conducting filler in at least one 15 but not all of said chambers, a constriction of said link being in a chamber containing the filler.

5. In an inclosed fuse, the combination of a casing, terminals at the ends of said casing, a pair of transversely disposed partitions within said casing, whereby the latter is divided into a central and two end chambers, a fusible link extending through said 20 chambers and between said terminals, said link being constricted in said central chamber and at least one of said end chambers, and a non-conducting filler in at least one 25 of said end chambers but not in said central chamber, a constriction of said link being in a chamber containing the filler.

6. In an inclosed fuse, the combination of a casing, terminals at the ends of said casing, a pair of transversely disposed partitions within said casing, whereby the latter 30

is divided into a central and two end chambers, a spacing member between said partitions, a fusible link extending through said chambers and between said terminals, said 40 link being constricted in said central chamber and at least one of said end chambers, and a non-conducting filler in at least one of said end chambers but not in said central chamber, a constriction of said link be- 45 ing in a chamber containing the filler.

7. In an inclosed fuse, the combination of a casing, terminals at the ends of said casing, a pair of transversely disposed partitions within said casing whereby the latter 50 is divided into a central and two end chambers, a fusible link extending through said chambers and between said terminals, said link having a portion of constricted cross-sectional area in each of said chambers, and 55 a non-conducting filler in each of said end chambers but not in said central chamber.

8. In a cartridge fuse, the combination of a casing, a perforated disk at the end of said casing, a fusible link extending through said 60 casing and said perforated disk, the end of said link being bent over the outer surfaces of said disk and said casing, a cap fitting over the end of said casing, said disk and the bent-over end of said link, and an 65 indentation in said cap extending into the bent-over end of said link and into the body of said casing, thereby anchoring said link and said cap in position.

In witness whereof I hereunto subscribe 70 my name this 30th day of July, A. D. 1915.

ALFRED L. EUSTICE.
